UNITED STATES PATENT OFFICE.

LEOPOLD SCHONWALD, OF NEW YORK, N. Y.

LOCK.

1,301,979.

Specification of Letters Patent. Patented Apr. 29, 1919.

Application filed October 26, 1917. Serial No. 198,576.

To all whom it may concern:

Be it known that I, LEOPOLD SCHONWALD, a citizen of the United States, and a resident of the borough of Manhattan, in the city, county, and State of New York, have invented certain new and useful Improvements in Locks, of which the following is a specification.

The improvements relate to locks for doors and the like, and are designed to produce a lock having a plurality of bolts operated by a key or other means and having features of construction which give great security against the opening of the lock by force or by improper manipulation.

The invention consists in the construction and arrangement of parts hereinafter described and claimed, and illustrated in the accompanying drawings, in which Figure 1 is an inside view of a lock embodying the improvements with the housing partly removed; Fig. 2 is a horizontal section of the same taken on the line 2-2 of Fig. 1; Fig. 3 is a view similar to Fig. 1 with the parts in position intermediate the locked position of Fig. 1 and their unlocked position; Fig. 4 is a vertical section on the line 4-4 of Fig. 3; Fig. 5 is a similar section on the line 5-5 of Fig. 3.

The housing of the lock consists of a hollow case A and cover A', these parts having a spread or enlargement A² at one end provided with lateral apertures A³ and a bolt hole A⁴ in the front, for the bolts. It is adapted to be secured to the inside of a door by means of the flanges A⁵ and A⁶, and the cover has a suitable key aperture while the case has an aperture in line therewith for the shank of the knob C.

The socket plate B consists of a flat portion with holes adapted to receive screws B', by which it is secured to the jamb or frame of the door, and suitable recesses B² and B³ to receive the horizontally acting and the vertically acting bolts respectively, after they are moved through the bolt holes of the lock housing. It will be seen that the enlarged portion of the lock extends beyond the edge of the door and passes into the space between the ends of the socket plate in which the bolt recesses A⁸ are located, so that the bolt holes in the casing and the bolt receiving recesses in the socket plate are in alignment when the door is closed.

The horizontal bolt D works in the slide E of the housing and in its bolt hole, at the

forward end of the case A, and is held against all movement except longitudinal movement thereby. Toward its forward end it is provided on its upper and lower edges with wings F having rounded outer extremities and projecting vertically therefrom. These flanges act against the arms G which are pivotally attached to the casing at G' and are pressed toward the bolt D by springs G². To the outer extremities of these pivoted arms G the round bolts H are pivoted, and therefore when the bolt D is moved forward toward its locking position, the wings F press the said bolts upwardly and downwardly through the arms G by bearing against the inclined surfaces of said arms. When the bolt D is withdrawn the bolts H are returned to their unlocked position by means of the springs G². A cam or other connection between the bolt D and the arms G may however be substituted for the springs.

The bolts are operated by the knob through the disk J with an extending arm J' and by the key, from the outside, through the disk K having an arm K' with a lug K² at its extremity. The disk J is keyed to the shank C' of the knob and the disk K is rotatably mounted in the plate A' and provided with a key-receiving slot or other device adapted to be engaged by the key for the purpose of rotating the disk. The bolt D has a cross-piece D' which limits the movement of the bolts in the locking direction by coming in contact with the end of the plate L, and the movement of the bolts in the opposite direction is checked when they have been retracted by contact between the tail of the bolt and the end of the track or slide E. The plate L is fixed to the inner wall of the case A and is provided with three recesses L, L² and L³ in its lower edge adapted to be engaged successively by the laterally projecting lug N² of the tumbler M, and the tumbler is pressed upwardly so that the lug will engage the said recesses by the spring O secured to the upper edge of the bolt D at one end and having its opposite end pressing against the rivet N, the end of which forms the lug N². The tumbler M is connected with a tumbler of similar form M' on the opposite side of the bolt D by means of this rivet, and also by means of the screw-bolt R passing through the said

tumblers and through the sliding plug P, so that all of these parts move together. The

plug P works vertically in the slot D² of the bolt D and holds the parts connected therewith against lateral movement.

When the disk J is rotated in counter-clockwise direction the extremity of its arm J' first comes in contact with the tumbler M at the notch or recess M² and depresses the tumbler so that the lug N' passes out of the recess L'. Further rotation of the disk withdraws the arm J' from the recess M² and permits the tumbler to rise under the pressure of the spring O until the lug N' rests in the recess L². The rotation of the disk is then continued until the arm J' engages the recess M³, depresses the tumbler and moves the said tumbler and the bolt forward until the lug N' is in alignment with the recess L³, when the withdrawal of the arm caused by further rotation permits the tumbler to rise again and the said lug to enter the said recess L³. In this position the bolts have been shot and are held in locked position by the engagement of the lug N' and the recess L³. The unlocking movement is the reverse of the movement just described, two rotations of the disk being required for each complete movement, and a relatively long movement of the bolts thus obtained. The operation of the lock by means of a key or other device from the outside is substantially the same, the part K² engaging the notches of the tumbler M' in the same manner as the notches of the tumbler M are engaged by the extremity of the arm J'. It will be seen that for ordinary purposes the locking and unlocking movements may be produced by a partial rotation of the knob and its disk arm or the key—as the case may be—causing the first movement described or the reverse movement, and a resulting half movement of the bolts. When, however, it is desired to lock the door or the like more securely—as on closing it for the night—the bolts may be moved to their extreme locking position, and security against forcing the lock thus obtained.

What I claim is:

1. The combination of a bolt, a part connected with said bolt and movable angularly with respect thereto, means for moving the said bolt, a fixed part mounted adjacent thereto and means for causing the engagement of said movable part and the said fixed part at different points in the movement of the bolt, said movable part having recesses arranged to be engaged successively and intermittently by the bolt-moving means, and said fixed part having recesses which are engaged by the said movable part when the bolt-moving means are out of operating engagement with said movable part.

2. The combination of a bolt, a movable member mounted thereon and adapted to move therewith, a single means for moving

the said bolt and also moving the said member in a direction angular to the movement of the bolt, means for automatically moving the said member with respect to said bolt when said member is released by the bolt-moving means, and a fixed member arranged to be engaged by the said movable member when it is so released, said fixed member having a plurality of recesses arranged to be engaged by the movable member successively and intermittently.

3. The combination of a bolt, a movable member mounted thereon and adapted to move therewith, a single means for moving the said bolt and also moving the said member in a direction angular to the movement of the bolt, means for automatically moving the said member with respect to said bolt when said member is released by the bolt-moving means, and a fixed member arranged to be engaged by the said movable member when it is so released, said fixed member having three recesses arranged to be engaged by a portion of said movable member when the bolt is in unlocked position and in its extreme locked position and when the said bolt is in an intermediate position.

4. The combination of a bolt, a movable member mounted thereon and adapted to move therewith, a single means for moving the said bolt and also moving the said member in a direction angular to the movement of the bolt, means for automatically moving the said member with respect to said bolt when said member is released by the bolt-moving means, and a fixed member arranged to be engaged by the said movable member when it is so released, said fixed member having a plurality of recesses, one arranged to be engaged by a portion of said movable member when the bolt is in its extreme locked position and another arranged to be engaged thereby when the bolt is in a position between its said extreme locked position and its unlocked position.

5. The combination of a bolt, a movable member mounted thereon and moving therewith in locking and unlocking direction of the bolt's movement, but having independent angular movement thereon, a bolt-moving device arranged to engage said member and to impart angular movement thereto, and also locking and unlocking movement of the bolt by a single movement of said bolt-moving device, said movable member on the bolt having a plurality of portions adapted to be engaged successively and intermittently by the bolt-moving device, and automatic means for returning said movable member to its normal position with respect to the bolt between said engagements, and a fixed member having a plurality of portions arranged to be engaged by said movable member successively and intermittently between the periods of its engagement by the bolt-moving device.

6. The combination of a bolt, a member mounted thereon to have angular movement only with respect thereto, said member having a plurality of recesses and a projecting portion, a bolt-actuating device adapted to engage said recesses successively and intermittently, and a fixed member having recesses adapted to be engaged by the said projecting portion, and automatic means for 10 causing said last named engagement, and the two said engagements occurring alternately.

7. In a lock, the combination with a suitable casing of a bolt, means adapted to be actuated by key mechanism for moving the

said bolt to locking and unlocking positions, 15 a second bolt mounted to move in a direction angular to the movement of the first named bolt, and means for imparting movement to the said second bolt through the movement of the first, said means comprising an arm 20 pivoted adjacent to both bolts, a spring normally holding said arm in the path of a portion of the first bolt and a connection between said arm and the second bolt.

Witness my hand this 17th day of October, 1917, at the city of New York, in the county and State of New York.

LEOPOLD SCHONWALD.
